(57) CLAIM

The ornamental design for a sports bottle, as shown and described.

DESCRIPTION

FIG. 1 is a top perspective view of a sports bottle showing our new design;

FIG. 2 is a bottom perspective view thereof;

FIG. 3 is a front elevational view thereof;

FIG. 4 is a rear elevational view thereof;

FIG. 5 is a right side elevational view thereof; the left side elevational view being a mirror image thereof;

FIG. 6 is a top plan view thereof; and,

FIG. 7 is a bottom plan view thereof.

The broken lines in the drawing depict portions of the sports bottle that form no part of the claimed design.

1 Claim, 7 Drawing Sheets
